UNITED STATES PATENT OFFICE.

LESLIE D. JANNELL, OF RUMFORD FALLS, MAINE.

BOB-SLED.

No. 888,888.

Specification of Letters Patent.

Patented May 26, 1908.

Application filed June 12, 1907. Serial No. 378,559.

To all whom it may concern:

Be it known that I, LESLIE D. JANNELL, of Rumford Falls, in the county of Oxford and State of Maine, have invented certain 5 new and useful Improvements in Bob-Sleds, of which the following is a specification.

This invention relates to sleds such as are used in logging operations for hauling logs, the chief parts of the sled being a pair of runners and a cross beam, usually termed a bunk, supported by the runners, and extending across the space between them, the bunk being elevated above the runners so that one end of a log may be placed upon and chained 10 to it, the other end of the log dragging on the track, or resting on the bunk of another sled.

My invention relates particularly to the means for connecting the bunk with the runners, and it has for its object to provide a 20 strong and serviceable attachment for a sled runner adapted to support one end of a bunk in a raised position above the runner, and to provide a loose connection between the bunk and runner which will permit a certain freedom 25 of independent movement of the runner relatively to the bunk, such as is required to prevent injurious or breaking strains when the sled is passing over rough roads.

The invention consists in the improved attachment which I will now proceed to describe and claim.

Of the accompanying drawings, forming a part of this specification,—Figure 1 represents a perspective view showing the runners 35 and bunk of a bobsled, the runners being provided with bunk-supporting attachments embodying my invention. Fig. 2 represents a side elevation of the same. Fig. 3 represents a longitudinal section of a portion of 40 one of the runners and of the attachment thereon. Fig. 4 represents an end view of the chair which forms a part of my improved attachment. Fig. 5 represents a section on line 5—5 of Fig. 2. Fig. 6 represents a section on line 6—6 of Fig. 2.

The same letters of reference indicate the same parts in all the figures.

In the drawings 12 12 represent a pair of sled runners, and 13 represents a bunk carried by the runners, and extending across the space between them, the bunk being elevated above the runners as usual.

My improved runner attachment for supporting the bunk, comprises an elongated base 14 adapted to bear on the upper edge of the runner 12, and having downwardly-pro-

jecting flanges 15 which bear on opposite sides of the runner, and are secured thereto by bolts 16.

17 17 represent brackets which project upwardly from the base, the base, its flanges and the brackets being preferably made of cast metal formed in a single piece. The brackets 17 have vertical inner faces which are separated from each other by a space 65 adapted to receive a chair 18 on which the bunk 13 bears. The chair is provided with upwardly-projecting ears 19, arranged to bear on opposite sides of the bunk, the bottom of the latter resting on the surface of the 70 chair between the ears. The chair is provided at opposite sides with outwardly-projecting lugs 20, which enter sockets 21 formed for their reception in the opposed inner faces of the brackets 17. The bottom of the chair is 75 provided with a downwardly-projecting lug 22, which enters a socket 23 formed for its reception in the intermediate portion of the base 14, which extends between the brackets 17. The lugs 20 and 22 of the chair fit 80 loosely in the sockets 21 and 23, so that the runner and the base member, with its brackets, are adapted to oscillate to a limited extent, both vertically and horizontally, independently of the chair and bunk, provision 85 being thus made for the independent play of the runners, which is necessary in traveling upon rough roads. 24 represents a cross bar, the ends of which are fitted in sockets 25 formed for their reception in the brackets 17, 90 said cross bar extending across the upper side of the chair between the ears 19, and preventing the chair from being lifted from the base and brackets. The cross bar 24 may be detachably secured to the brackets 95 by pins 26, or by any other suitable means. The chair may be provided with ears 27 at opposite edges of the cross bar, the latter fitting loosely between the ears and assisting the lugs and sockets, above mentioned, in 100 limiting endwise movement of the chair relatively to the base.

The chair is preferably a single piece or casting, comprising a relatively narrow foot 28, which bears on the base 14, a head 29 105 which is longer than the foot, and forms a seat for the bunk 13, side webs 30, connecting the foot with the head, and a transverse web 31 extending between the side webs 30. From the opposite edges of the head 29, the 110 ears 19 project upwardly. There are preferably two pairs of ears on the head, the ears of

one pair being higher than those of the other. The higher ears project above the permanent bunk 13, and are adapted to engage a supplemental bunk 32, which is used when the sled is used for dragging logs, their rear ends trailing behind the sled. When only one bunk is employed, the ears should both be of the same height.

Each bracket 17 is preferably composed of a vertical arm 170, projecting upwardly from the base, and forming one end of the chair-receiving opening, and an inclined brace 171, which is preferably curved, as shown, the said brace securely supporting the arm, and by reason of its curved form, opposing effective resistance to shocks or blows which it may receive from logs, etc. The space between the arm 170 and the brace 171 is preferably occupied by a web 172.

One of the brackets 17 is provided with an ear or projection 33 adapted to engage a skid or short log which is placed on one of the brackets in an inclined position, one end resting on the bracket and being confined thereon by the ear 33, while the other end rests on the ground at one side of the sled. The skid is used to facilitate the loading of logs, one end of the log being rolled upon the skid onto the bunk.

It will be observed that the lugs 20 project

outwardly from opposite vertical sides of the chair, so that the points of contact between the lugs and the brackets with which they are loosely engaged have the maximum outward extension from the center of the chair, and the maximum separation from each other. Sufficient leverage is thus provided to withstand the shocks and stresses to which the sled is subjected when in use.

I claim:

A sled runner attachment comprising a base adapted to bear on a runner and having upwardly-projecting arms forming sides of a chair-receiving opening, said arms and the intermediate portion of the base being provided with sockets, and a chair composed of a foot bearing on the intermediate portion of the base, a head forming a bunk seat, side webs connecting the head with the foot, a transverse web connecting the side webs, and bunk-engaging ears projecting upwardly from the head, the foot and the side webs of the chair being provided with lugs which loosely engage said sockets.

In testimony whereof I have affixed my signature, in presence of two witnesses.

LESLIE D. JANNELL.
